BASE FOR A TELEPHONE SET

Paul Marchese, Greenwich, Conn., assigner to
TIE/communications, Inc., Stamford, Conn.

Filed Apr. 4, 1974, Ser. No. 458,016

Term of patent 14 years

Int. Cl. D14—03

U.S. Cl. D26—14 A

FIG. 1 is a top plan view of a telephone base showing my new design;

FIG. 2 is a front plan view of the telephone base of FIG. 1;

FIG. 3 is a rear plan view of the telephone base of FIG. 1;

FIG. 4 is a left plan view of the telephone base of FIG. 1;

FIG. 5 is a right plan view of the telephone base of FIG. 1;

FIG. 6 is a front perspective view of the telephone base of FIG. 1;

FIG. 7 is a top plan view of a second modified embodiment of a telephone base showing my new design;

FIG. 8 is a front plan view of the telephone base of FIG. 7;

FIG. 9 is a rear plan view of the telephone base of FIG. 7;

FIG. 10 is a left plan view of the telephone base of FIG. 7;

FIG. 11 is a right plan view of the telephone base of FIG. 7;

FIG. 12 is a front perspective view of the telephone base of FIG. 7.

In the figures the broken lines representing the handset are shown for illustrative purposes only.

I claim:

The ornamental design for a base for a telephone set, substantially as shown and described.
